AUTOMATIC LOCK SLIDER

Louis H. Morin, Bronx, N. Y., assignor to White-hall Patents Corporation, Bronx, N. Y., a corporation of New York

Application January 7, 1939, Serial No. 249,745

12 Claims. (Cl. 24—205.5)

This invention relates to the sliders of separable slide fasteners employing stringers adapted to be coupled and uncoupled in the movement of a slider longitudinally of the stringers. More particularly, the invention relates to an automatic locking slider; that is to say, a slider having locking means which is automatically moved into and retained in operative position in retaining the slider against accidental movement longitudinally of the stringers and whereby the movement of the finger piece or pull against the action of tensional means employed will operate to move the lock element into raised inoperative position permitting free movement of the slider longitudinally of the stringers. The novel features of the invention will be best understood from the following description and annexed drawing in which certain embodiments of the invention are disclosed, and in which the separate parts are designated by suitable reference characters in each of the views, and in which:

Fig. 1 is a face view of a part of a fastener with the slider arranged thereon with parts of the construction broken away.

Fig. 2 is a partial section on the line 2—2 of Fig. 1.

Fig. 3 is a bottom plan view of the pivot end of a pull which is employed, detached and with part in section; and,

Fig. 4 is a view similar to Fig. 2 showing a modification.

In Fig. 1 of the drawing is shown at 10, 10a, the stringers of a separable fastener having coupling links 11 arranged thereon, and at 12 is shown a slider movable longitudinally of the stringers to couple and uncouple the same. The body portion of the slider is of more or less conventional form except as more specifically herein-after defined. By general conventional form it is meant that the slider consists of a channeled body having top and bottom walls joined centrally of one end in a connecting web, part of which is seen at 13 in Fig. 2 of the drawing, which web divides the body into diverging chan-

nels at the wide end portion thereof. The upper wall 14 of the slider is provided with transversely spaced upwardly projecting lugs 15, the outer surfaces of which are preferably rounded as clearly seen in Fig. 1 of the drawing, and intermediate the lugs 15, the outer surface of the wall 14 is recessed as seen at 16. The wall 14 is also provided with an elongated aperture 17 adjacent one of the bearing lugs 15, and this aperture also opens into the recess 16 as will be apparent. The wall 14 is further pro-

vided with an aperture 18 which opens into the recess 16.

At 19 is shown a part of a finger piece or pull, primarily the pivot end portion thereof. This end portion terminates at its free end in two cylindrical side bearings 20, joined by an arc-shaped hood portion 21 which forms between the bearings a chamber 22 for the reception of a coil spring 23. The spring 23 is arranged around the coupling or pivot pin 24 or that part thereof which is disposed in the chamber 22. The pin passes through apertures 20a formed in the bearings 20 and also extends into the lugs 15 and may be riveted or otherwise secured in position to form a pivotal coupling of the pull 19 with the slider. One end 23a of the spring extends into an aperture or socket 25 in the pull 19, the latter opening into the chamber 22; and the other end 23b of the spring extends into the aperture 18 in the pull. The arrangement of the spring ends and winding of the spring is such as to place the pull 19 under tension so as to retain the pull normally in an operative position; that is to say, in abutting engagement with the top wall 14 of the slider. In other words, the upward swinging movement of the pull on the pivot 24 will be against the tension of the spring 23.

In the construction shown in Figs. 1 and 2 of the drawing, the finger piece is provided with a downwardly projecting lock pin or pawl 26 arranged in registering alignment with the aperture 17 so that when the finger piece is in its normal position, the end of the pin or pawl 26 extends into the channel of the slider to engage at least one of the stringer links to retain the slider against accidental movement longitudinally of the stringers. At this time it is well to point out that one of the distinctive features of the invention resides in the provision of the tensional means which normally supports the coupling pin or pawl of the pull in operative position. While it is possible under excessive stresses and strains to disengage the pawl from one link to move the sliders longitudinally of the stringers, the pawl will, nevertheless, be immediately moved into further locking engagement producing a decided ratchet effect. This operation is distinctly different from the more conventional type of pin lock where it is commonly experienced that when the pin once becomes accidentally disengaged, it will stay disengaged for the full period of a given stress or strain.

With the present construction, it will appear that the coil spring 23 is used within and concealed by the hood portion 21. This hood por-

tion is free to extend around the spring and to enter the chamber 22 in the upward swinging movement of the finger piece 19 as will readily appear from a consideration of Fig. 2 of the drawing. Sufficient clearance is provided to compensate for raising the pull sufficiently to operate the slider in both directions on the stringer.

In addition to the concealment of the spring, which produces a neat and finished appearance of the complete pull, it will also appear that a very simple assemblage job is provided; that is to say, the spring is first mounted in the socket portion housed by the hood 21 of the pull with the end 23a mounted in the aperture 25, and with the end 24 extending downwardly. As a matter of fact, before the tension is taken up, the end 23b will extend somewhat in the direction of the end 23a but will protrude through the bottom of the pull. The parts thus assembled will readily be placed upon the slider by inserting the spring end 23b into the aperture 18, then moving the pull in the direction of the contracted end of the slider, placing the spring 23 under tension in this operation, and bringing the apertures 20a in alignment with the corresponding apertures in the lugs 15, and then placing the pin 24 in position.

In Fig. 4 of the drawing is shown a slight modification of the construction shown in Figs. 1 and 2 wherein I have substituted for the pull 19, a pull 19a which differs from the pull 19 solely in being provided with an independent lock pin or pawl element 27 which is preferably made independent of the pull 19a and secured thereto; whereas in the structure shown in Figs. 1 and 2, the pin or pawl 26 is formed integrally with the pull, the entire structure being in the form of a die casting.

The structure in Fig. 4 is adapted primarily for use in such instances where the pull 19a, as well as the slider 12a, are composed of thermoplastic materials, such for example as cellulose acetate, or in fact, or any of the plastics; and further where the slider is arranged upon correspondingly formed stringers. In such instances, the lock pin or pawl 27 may be composed of metal or other hard wearing material which will not be subject to breakage. It will also appear that the pin or pull 27 is located slightly beyond the pivot 24a of the pull and operates in an aperture 11a correspondingly arranged in the slider. Otherwise the structure shown in Fig. 4 is substantially the same as that shown in Fig. 2, the hood of the pull being shown at 21a and the recess in the slider being shown at 16a.

In view of the disclosure, it will appear that one of the features of the invention resides in the provision of a housing at the pivot end of the pull and formed by what is termed a hood portion, and in arranging in this housing resilient means, such for example as the spring, so acting upon the pull as to normally support the pull upon the outer surface of the slider and retain the same against accidental displacement. While this construction is applied to what is commonly termed a lock slider, it will, of course, be apparent that the lock element need not necessarily be employed, except where this feature is desirable. It will further be understood that the illustrations in the accompanying drawing are simply to show certain adaptations of the invention, but the invention is applicable to sliders of various types and kinds. It will be apparent that the pull may be so mounted and the slider so constructed as to normally support the pull at the wide end portion of the slider, especially in adapting the

fastener to be used in conjunction with leggings, or to other adaptations where the so-called reverse lock slider is employed.

Having fully described my invention, what I claim as new and desire to secure by Letters Patent, is:

1. A lock slider for separable fasteners of the character described, said slider comprising a channeled body, a pull pivotally supported upon one outer wall of the slider, said pull having adjacent the pivot thereof a projecting lock element adapted to protrude through one wall of the slider to extend into the channel thereof when the pull is arranged in horizontal position upon the slider wall, and a spring housed within the pivot end of the pull and cooperating with the slider and pull to normally support the pull in tensional engagement with the wall of the slider to maintain the lock element in operative position. 10

2. A lock slider for separable fastener stringers of the class described, said slider comprising a channeled body having a pair of projecting lugs on one wall thereof, a pull, means pivoting one end portion of the pull in said lugs, said pull having a projecting lock element adapted to normally extend into the channel of the slider, a coil spring arranged within the pivot end portion of the pull with one end portion of the spring engaging the slider and the other end portion thereof engaging said pull the spring being under tension to normally support the pull in a position projecting the lock element thereof into the channel of the slider whereby the movement of the pull to withdraw the lock element from the channel of the slider will increase the tension upon 30 said spring. 30

3. In separable fasteners employing stringers and a slider movable along the stringers to couple and uncouple the same, the slider having means for pivotally supporting a pull in connection therewith, a pull having at the pivot end portion thereof, a curved hood forming a chamber within said pull, a coil spring arranged within said chamber with one end of the spring engaging said pull and the other end thereof engaging the slider to normally and tensionally support the body, portion of the pull upon the upper surface of the slider, and the pivot end portion of the pull having a projecting lock element engaging one of the stringers in the normal position of said pull. 40

4. A pull for sliders of separable fastener stringers, one end portion of the pull having means receiving a pivot pin for pivoting the pull to a slider, a substantially semi-circular hood portion at the pivot end of the pull and extending around the pivot axis thereof, the hood being disposed upon the outer surface of the pull, the inner surface of the pull having a projecting latch element, a coil spring arranged within the hood portion of the pull and concealed by said hood portion, said spring engaging the pull to normally support the latch element thereof in operative position. 50

5. A slider of the class described having on one outer wall thereof spaced apertured lugs, a pull, one end portion of which is provided at each side thereof with cylindrical apertured bearings, a pivot pin passed through the lugs and the bearings of said pull to pivot the pull in connection with said slider, a curved hood portion on the pull intermediate said bearings forming a chamber around said pin within said hood portion, a coil spring arranged in said chamber with one end of the spring engaging the slider and the other end thereof engaging the pull, the spring tension be- 60

ing such as to normally support the body portion of the pull in substantially parallel relation to the outer wall of said slider.

6. A slider of the class described having on one outer wall thereof spaced apertured lugs, a pull, one end portion of which is provided at each side thereof with cylindrical apertured bearings, a pivot pin passed through the lugs and the bearings of said pull to pivot the pull in connection with said slider, a curved hood portion on the pull intermediate said bearings forming a chamber around said pin within said hood portion, a coil spring arranged in said chamber with one end of the spring engaging the slider and the other end thereof engaging the pull, the spring tension being such as to normally support the body portion of the pull in substantially parallel relation to the outer wall of said slider, and the outer wall of the slider intermediate said lugs being recessed 20 to receive the bearings and hood portion of said pull in the swinging movement of the pull on the slider.

7. A slider of the class described having on one outer wall thereof spaced apertured lugs, a pull, one end portion of which is provided at each side thereof with cylindrical apertured bearings, a pivot pin passed through the lugs and the bearings of said pull to pivot the pull in connection with said slider, a curved hood portion on the 25 pull intermediate said bearings forming a chamber around said pin within said hood portion, a coil spring arranged in said chamber with one end of the spring engaging the slider and the other end thereof engaging the pull, the spring tension being such as to normally support the body portion of the pull in substantially parallel relation to the outer wall of said slider, the outer wall of the slider intermediate said lugs being recessed to receive the bearings and hood portion of said 30 pull in the swinging movement of the pull on the slider, the outer surface of the hood being in alignment with the outer surfaces of said bearings to form a substantially cylindrical end portion at the pivot end of the pull, and said pivot 35 end of the pull having a projecting lock element adapted to extend into the slider in retaining the slider in operative position.

8. A slider of the class described comprising spaced walls joined by a connecting web at one end, a pull, means pivotally connecting one end of the pull to one wall of the slider, the pivot end of the pull having a hood portion, resilient means within the hood portion of the pull cooperating with the slider wall and pull to normally support 50 the free end portion of the pull tensionally in engagement with the wall of the slider, said wall of the slider having an aperture, and the pull

having a projecting pin member adapted to extend through the aperture in said wall into the slider when the pull is supported in engagement with said wall.

9. A slider of the class described comprising 5 spaced walls joined by a connecting web at one end, a pull, one wall of the slider having on the outer surface thereof a pull pivot, a pin pivoting one end of the pull to said pull pivot, a coil spring arranged upon said pin with the ends of said 10 spring engaging the slider and the pull to normally support the pull in tensional engagement with said wall of the slider whereby in releasing the pull when manually supported in raised position with respect to said wall, the spring will 15 automatically return the pull to engagement with said wall.

10. A lock slider for separable fasteners of the character described, said slider comprising a channeled body having spaced walls joined by a 20 connecting web at one end, a member pivotally supported in connection with one wall of the slider, said member having a projecting lock element 25 adapted to protrude through one wall of the slider to extend into the channel thereof, a coil spring arranged upon the pivot of said member, said spring tensionally engaging the member to normally support the lock element within the channel of said slider, and said member being adapted to be manually raised against the tension 30 of said spring to move the lock element out of the channel of the slider in the operation of said slider.

11. In separable fastener stringers, a slider, a pull, means at one end of the pull and on said 35 slider pivotally coupling the pull in connection therewith, said end portion of the pull having a curved hood forming a chamber within said pull, a spring arranged within the hood and concealed thereby, and said spring having portions 40 engaging the pull and the slider to automatically maintain the pull in predetermined position upon the slider.

12. A pull for pivotal mounting upon sliders of separable fastener stringers, said pull comprising 45 an elongated body, a curved hood portion at the pivot end of said body, spaced apertured pivot pin bearings within said hood portion adapting the pull for pivotal mounting in connection with a slider, and the hood portion of the pull intermediate 50 said bearings forming a chamber of materially greater diameter than the diameter of the apertures in said bearings to limit frictional engagement of the pivot end of the pull with the apertured bearing portions only thereof. 55

LOUIS H. MORIN.
